H. J. DAVIES.

Pedestals and Fronts of Clock Cases.

No. 11,902.

Patented Aug. 3, 1880.

UNITED STATES PATENT OFFICE.

HENRY J. DAVIES, OF BROOKLYN, NEW YORK.

DESIGN FOR PEDESTAL AND FRONT OF CLOCK-CASES.

SPECIFICATION forming part of Design No. 11,902, dated August 3, 1880.

Application filed May 18, 1880. Term of patent 7 years.

To all whom it may concern:

Be it known that I, HENRY J. DAVIES, of Brooklyn, in the county of Kings and State of New York, have originated a new and Improved Design for the Pedestals and Fronts of Clock-Cases, of which the following is a specification.

The character of my design is clearly illustrated in the accompanying drawing, which 10 represents a perspective view of a clock-case embodying my design.

The pedestal of the clock-case is composed of the bar A of parallelopipedal form, and the subbase A' molded, as represented. The base 15 A is represented as striated upon its front and sides, as indicated by the letters a a, and has bas-relief ornaments b b at the corners.

The surmounting body B of the case has a nearly flat front, straight upright sides, and a 20 peaked top, C, sloping upward from each side to a central ridge. The front of the body portion of the case is also striated in a manner similar to the base along the margin of the lower part, the upright sides, and the top, as 25 indicated by the letters c c.

Upon the front of the body portion B of the case, at the angles formed between the upright sides and the sloping top portions, and also at or under the point or peak of the top, 30 are bas-relief ornaments d d d.

What I claim as my invention, and desire to secure by Letters Patent, is—

1. The design for the pedestal and front of a clock-case, consisting of the parallelopipedal base A, having straight striations a, the molded subbase A', the straight upright sides, and sloping peaked top C, having straight striation c, and the bas-relief ornamental caps d d on the point of the peaked top and at the angles between upright sides and the sloping 35 top portions, all substantially as shown and herein described.

2. The design for clock-case, consisting of the parallelopipedal base A, the molded subbase A', the upright sides terminating in the 40 sloping peaked top C, said base A, upright sides, and sloping top having the straight parallel striations a c c, substantially as shown and herein described.

3. The design for a clock-case, consisting of 45 the parallelopipedal base A, striated as indicated by the letters a a, and having bas-relief corner ornaments, b b, the molded subbase A', the body portion B, having parallel upright sides and a peaked top, C, and striated upon 50 its front, as indicated by the letters c c, and bas-relief ornaments d d d, substantially as 55 specified.

HENRY J. DAVIES.
